DEVICE FOR CURLING AND LOCKING HAIR

Angelo Cuomo, Brooklyn, N. Y.

Application August 23, 1937, Serial No. 160,376

10 Claims. (Cl. 132—33)

My invention relates to a device for curling and locking hair. More particularly, it relates to an improved hair curling and hair lock holding device for curling locks of hair and then clamping the locks into fixed position.

In the hair treating art various types of curlers are used for turning locks of hair and then clamping them. In some cases, a hair curler is provided which has an extended wire portion turnable over the hair curl thereby clamping the same. In such cases the curler is too bulky and many are required for the hair thereby imparting an unpleasant appearance to the wearer. In order to offset this disadvantage, hair curlers are provided by which hair pins of ripple longitudinal shape commonly known as "bobbie" pins are used on the heads of the wearer. Such bobbie pins, however, are difficult to spread and hold the hair locks.

With the above and other disadvantages in view, it is an object of my invention to provide an easily operable device for curling and clamping locks of hair, which can be easily removed after the curling operation without disarranging the tufts of the hair locks.

Another object of the present invention is to provide a novel easily constructed device adapted to carry a hair pin and curl locks of hair and then shoot the pin thru the curl preparatory to clamping the same.

One other object of the present invention is to provide a novel hair curling device adapted to cooperate with a novel "springy" hair pin for easily clamping locks of hair.

Another object of my invention is to provide a novel hair pin which can be easily projected thru a hair lock and be closed to clamp the hair lock.

The above and other objects of my invention will become apparent from the following detailed description of preferred embodiments thereof, taken in connection with the accompanying drawings in which:

Figure 1 is a longitudinal, partly sectional view of a preferred embodiment, loaded with a curl holding pin which also forms a part of the invention.

Figure 2 is a partly sectional plan view of Figure 1, showing a hair lock curled and the position of the hair pin ready to be locked and clamp the hair curl.

Figure 3 is a plan view of a hair curl clamped with one of my new hair pins.

Figure 4 is an end view of Figure 3.

Figure 5 is a slightly enlarged elevation of a

novel hair pin forming part of my invention, in which the straight end is rotated clockwise to close the pin.

Figure 6 is an elevation of a modification of the pin in Figure 5, in which the straight end is rotated counterclockwise to close the pin. 5

Figure 7 is a partly sectional plan view of a modification of the embodiment shown in Figure 1; and 10

Figure 8 is a section taken on line 8—8 of Figure 2.

In the drawing, like numbers refer to like parts throughout.

Referring now more particularly to the drawing, a hollow tube or cylindrical member 10 is provided with a pair of opposed parallel longitudinal slots 11 and 12 respectively, and is adapted to accommodate a wire compression spring 13, and a concentric tubular carriage 14 slidable 15 in tube 10 by means of the spring when under compression.

Tube 10 adjacent one of its ends is provided with a detent 15 pivoted thereto by means of a cross pin 16. Said pin extends thru the tube 25 above the center of its cross section thereby forming a segment of the tube. Furthermore, the pin extends thru the lower portion 17 of the detent to permit proper leverage action of the handle 18 when moved in a downward ar- 30 cuate position, as indicated by the arrow in Figures 1 and 2.

Said tube 10 is also provided with an opening 19 in alignment with the detent to accommodate the engaging end 20 of detent 15. Said 35 end 20 forms a lock with recess 21 of the carriage when the latter is pushed into operative position as shown in Figure 1.

Spring 13 is fixed at one end 22 to detent 15 at a point below its pivotal portion and at the 40 other end 23 to the carriage 14. Said carriage is provided with a cross member 24 having its ends projecting outwardly of slots 11 and 12 respectively, to permit easy sliding of the carriage 14 toward the detent thereby compressing 45 spring 13. It is to be noted that when spring 13 is being compressed it automatically actuates detent 15 on its pivot to form an automatic locking engagement with the carriage, as shown in Figure 1 of the drawing. Also, when the detent 50 is actuated, spring 13 normally extends longitudinally in member 10.

Integral with said carriage 14 is an extended inner tube 25 of relatively smaller diameter than tube 10. Said tube 25 is preferably disposed ec- 55

centrically with respect to tube 10 and is provided with a longitudinal opening 26 coincidental with a longitudinal opening 27 in tube 10 for carrying a hair pin 28 which will be further described. The plane of said latter longitudinal opening is preferably at right angles to the plane of slots 11 and 12.

Tube 10 is further provided intermediate its ends and in alignment with detent 15 with a pair of spaced parallel ears 29 onto which is pivoted a tapering tubular member 30 for fastening hair strands against the adjacent or abutting portion of tube 10. Said fastening member 30 is of reduced curvate cross section and is pivoted to ears 29 by means of a cross pin 31 intermediate the ends of said members. There is also provided a finger rest portion 32 while the major length portion 33 of the member is used for retaining hair against tube 10. In order to keep portion 33 of member 30 against tube 10, there is provided a spring plate 34 curled around cross pin 31 and between ears 29, one end of said plate abutting tube 10, while the other end abuts the underside of hand rest 32 as shown in Figures 1 and 2 of the drawing.

Hair pin 28, as shown in the accompanying drawing, is of novel construction in that it is easy to use for clamping hair and can be easily applied in contrast with the rippled and other types of "bobbie" pins now in use. The novel hair pin I have shown is preferably made of spring wire of any desirable length which is then bent in two forming a loop 34' and a straight end 35. The other end 36 of the pin is provided with a curl or twist 37 adapted to accommodate the straight end of the pin as shown in Figures 3 and 4 thereby clamping a curl of hair lock in fixed position after the curling operation.

Said pins are made, wherein the straight end 40 is twisted around the loop 34' as a center, in a clockwise direction forming engagement with twist 37. Such a pin 38 is shown in Figure 5, while in Figure 6, I show a pin 39 in which straight end 40 is turned in a counter clockwise 45 direction to engage twist 41. While I have shown preferred novel forms of pins used in my invention, I have found that pins in which each free end is provided with a twist can also be effectively used.

In Figure 7, there is shown a modification of Figures 1 and 2. In said modification, tube 42 is provided with a pair of parallel slots 43 open at one end of the tube for taking up a lock of hair and permit the curling of said lock. A slideable carriage and pin holder 44 in the tube is provided which can be slid thru the tube 10 by means of members 45 and 46 extending outwardly therefrom and from a pair of opposed parallel slots 47 and 48 respectively. It is to be noted that 60 the carriage is actuated by hand in the curl binding operation.

In the hair curling operation according to my invention, a pin 28 is set with the looped portion into carriage tube 25 against one end of the carriage 14 thereby leaving the twisted or curled end of the pin exposed from longitudinal opening 27. Carriage 14 is then pushed by means of cross member 24 against the action of spring 13 toward the detent end of the tube until it is in engagement with detent hook 20. The curler having been thus loaded, the end of a lock of hair 49 is then held between fastener 33 and the adjacent end of tube 10, and curled until a curl of sufficient size is obtained. The operator then releases carriage 14 by pressing detent handle 18

downward in the direction of the arrow shown in Figures 1 and 2, whereupon the carriage is sprung back to its normal position by means of compression spring 13. The pin 28 is also carried with the twisted end 36 outside the curl, while the straight end 35 is still in tube 10. The operator then locks the pin as shown in Figures 3 and 4 and then withdraws the device from the locked curl.

It is to be noted that by my invention, as described in connection with the accompanying drawing, no hair pulling or hurting of fingers because of "bobbie" pins is present. There is an easy insertion of the hair pin thru the curled hair lock and clamping of the same with a minimum expenditure of time. Furthermore, the parts embodying my invention may be made of any suitable metal such as iron, brass or aluminum.

My invention is very useful not only for women at home who fix up their own hair, but also for beauty parlor operators where time is important in serving many people.

While preferred embodiments of the invention have been described in connection with the accompanying drawing it is to be noted that modifications as to form, size, arrangement and use of materials may be made without departing from the scope and spirit of my invention as set forth in the following claims.

I claim:

1. A device for working hair comprising a tubular member, hair fastening means pivotally mounted on said member, compressed pin pushing means, slideable axially in said member, and terminal automatic locking means on said member for retaining said pin carrying and pushing means and adapted to release said carrying means, and permit clamping of a hair curl formed by said device.

2. A device for curling and clamping hair, comprising a tubular member, hair fastening means pivotally mounted on said member, means slideable in the tubular member for carrying an open hair pin and normal compression means automatically forcing the slideable means toward the hair fastening end of the tubular member to insert said hair pin thru the hair curl and clamp the same.

3. A device for curling and clamping hair, comprising slotted tubular hair fastening means, curling means in connection with said first means, a carrying member longitudinally slideable in the curling means, a compression spring member fixed to the tubular means adapted to normally force the carrying member toward the slotted portion of the hair fastening means, and an open hair pin mounted in said carrying member insertable thru a hair curl and adapted to clamp the same in fixed position.

4. A device for curling and clamping hair, comprising tubular member for curling hair, a member associated with said tubular member for fixing the hair in position prior to curling, a carriage in said member for retaining an open twistable hair pin with one of its ends normally projecting from the means, compression spring means in the tubular member for normally forcing said carriage toward one end of the tubular member with the open twistable hair pin in said carriage, said pin being adapted to be slid thru the formed hair curl and clamp the same.

5. A device according to claim 4 in which there is provided an automatic locking member pivoted adjacent one terminal portion of the tubular member for retaining the carriage under com-

30

pression prior to clamping a formed hair lock.

6. A device for curling and clamping hair comprising pivotal fastening means to retain the free ends of hair, a tubular member in association with said means for curling strands of hair, a pin carriage axially slidble in said member, resilient tension compression means extending axially in the tubular member in connection with the carriage adapted to project said carriage toward one end of the member, and automatic locking means mounted on one end of said member for engaging the carriage and retain the same under compression while the hair is being curled, said carriage carrying a hair pin adapted upon release of the carriage by the locking means to be projected thru a hair curl and to clamp the same.

7. A hair curling and clamping device for hair, comprising a tubular member, a tensioned hair fastening member externally pivoted to the tubular member, a hairpin carriage slidble in said tubular member, an actuatable detent at one terminal portion of the member for automatically engaging the carriage, when pushed toward said detent, compression means intermediate the detent and the carriage to retain the latter under compression, and cross means projecting perpendicularly from the carriage externally of the tubular member to actuate the carriage into engagement with the detent, said carriage being adapted to carry a hair pin whereby upon curling the hair, and upon release of the detent the pin is projected thru a curl of hair preparatory to clamping the latter.

35 8. A device according to claim 7, in which the carriage upon being moved toward the detent compresses the spring to automatically actuate the detent and form a locking engagement with the carriage.

9. A hair curling and clamping device comprising a tubular slotted curling member, tensioned means pivoted intermediate its ends to the curling member forming an abutting contact at one of its ends with the member for fastening the ends of the hair to be curled, a projectible carriage slidble in the member, a manually actuatable detent pivoted to one end of the member for automatically engaging the carriage, a compression spring member interconnecting the detent and the carriage, grasping means projecting laterally of the carriage and from slots of the curling member for actuating the carriage into engagement with the detent, an extension on the carriage having a longitudinal opening corresponding with a longitudinal opening in the curling member adapted to carry an open hairpin in said extension, said pin having an end projecting from the opening of the curling member when the carriage is in locked position, whereby upon release of the detent the pin passes through the curl formed by the curling member and is adapted to clamp the curl.

10. A device for curling and holding hair comprising a tubular member, means on the member adapted to retain a lock of hair and permit curling of the same, compression spring means fixed at one end to the terminal portion of the member and slidble in the member and adapted to retain an open lockable hair pin thereon and in the member, a manually operable detent member mounted on the tubular member adapted to automatically engage the means when the latter is pushed toward the detent and during the curling of the hair and permit ejection of the pin thru the hair lock.

ANGELO CUOMO.
